CLOSURE RETAINING MEANS FOR
CONTAINERSFrank L. Lloyd, Baltimore, Md., assignor to
Crown Cork & Seal Company, Inc., Baltimore,
Md., a corporation of New York

Application November 22, 1937, Serial No. 175,938

4 Claims. (Cl. 215—90)

The present invention relates to containers and means for securing covers thereon, the containers herein principally contemplated being in the forms of jars. An object of the invention is to provide an arrangement wherein the securing means, in the form of clips, are readily applicable in use and securely hold the cover on the jar while permitting it to lift to vent under excess internal pressure, the clips when moved to release the cover being entirely separable from both the cover and the jar so that the latter may be effectively cleaned.

Embodiments of the invention are shown by way of example in the accompanying drawing in which:

Figure 1 is a substantially axial section of a jar and cover showing a pair of clips according to the invention in elevation and in cover-securing position;

Figure 2 is a plan view of the unit of Figure 1; Figure 3 is a partial axial section of a jar and cover showing a slightly modified form of jar finish and clip;

Figure 4 is a partial axial view of a cover and jar similar to that of Figure 3 and showing a pair of clips according to the present invention strung on a retaining and positioning wire;

Figure 5 shows in perspective the clips and wire of Figure 4, and

Figure 6 is a partial axial section of a cover and jar showing a further modified form of clip in elevation.

Referring first to Figures 1 and 2, reference numeral 10 designates a container in the form of a jar which may be of glass and of substantially cylindrical form as shown. At its mouth the inner walls of the container are somewhat outwardly flared at 11 up to the lip 12 which may have annular ribs formed therein as shown. The upper extremity of the jar has an outer annular enlargement 13 which provides a downwardly faced shoulder 14 which may be somewhat undercut as shown.

The cover 15 has a marginal portion 16, annularly ribbed, if desired, adapted to overlie the lip 12. Inwardly of the margin 16 the cover is downwardly offset to provide a depressed central portion 17 which fits easily within the flared portion 11 of the jar to center the cover. At its outer edge the cover is provided with a relatively thin upstanding annular rib 17a. Inwardly of rib 17a are flat annular seating surfaces 17b which may be bounded circumferentially by lugs 17c.

Each clip 18 consists of a strip of relatively

heavy springy, but deformable, metal, bent to provide the two angularly related portions 19 and 20, and as shown, these portions are about at right angles to each other. The extremity of portion 19 is bent inwardly to provide a hook 21 engageable under shoulder 14. The portion 20 has a bent-under portion 22 which extends into proximity to portion 19, and it and the superjacent portion may be slightly bent as at 23 and 24, these portions normally being in about parallel relation.

To apply a clip, the free end of its portion 22, which is of a width to be receivable between a set of lugs 17c is placed on a seat 17b and then the remainder of the clip is depressed and swung to bring hook 21 under shoulder 14, portion 19 thus being placed under considerable tension so that a gasket 25 is suitably compressed. Preferably, both clips are simultaneously applied.

It will be seen that the extremities of clip portions 22 lie behind rib 17a which serves as a positive stop for them, and since the hooked ends 21 are engaged with the undercut shoulder 14, the cover is held securely in place and the clips are not apt to be accidentally dislodged even when the cover lifts to relieve internal pressure. When it is desired to remove the clips, it is only necessary to engage the bent free end portions of the substantially horizontally extending clip portions 20 and lift them upwardly and outwardly, portions 22 flexing toward the superjacent clip portions as they slide upwardly and over rib 17a, there being a pivoting action about the hooked portions 21 until release is effected.

Since the clips are entirely separable from the container and the cover, all of the parts may be readily and effectively cleaned.

According to Figure 3 the shoulder 26 of the jar is in a plane substantially normal to the jar axis. The portion 27 of the clip has its intermediate portion 28 slightly bent outwardly so as to make sure that any outward expansion of the gasket 29 will be amply accommodated. Further, the bent-under portion 30 of the clip is provided with an intermediate bend 31 toward the superjacent clip portion.

According to Figures 4 and 5 the clips 32 are strung on a continuous wire 33 and are provided with bends 34 such that the engaged portions of the wire will be retained. The main portion of the wire is downwardly offset to lie closely adjacent the top of the cover, this conformation serving also to position the clips exactly opposite each other, as will be evident.

A greater number than two clips may be pro-

55

vided for each jar, and where a wire, such as at 33, is utilized, it may be correspondingly bent to position the clips equidistantly. On the other hand, a purely circular wire may be used and the clips freely strung thereon.

5 The clip 35 of Figure 6 is the same as that of Figure 3, except that the hooked end 36 is continued into a bent-out tail 37 which may be gripped so that the hook may be pulled outwardly 10 from under shoulder 38 to release the clip.

It will be understood that various modifications in detail may be made from the disclosure herein without departure from the invention as defined in the following claims.

15 I claim:

1. The combination with a container in the form of a jar, said container having an external downwardly faced shoulder, and a cover for the mouth of the container having a marginal portion overlying the container lip, of means for securing the cover on the container, said means comprising a plurality of clips each of which comprises a strip of springy metal bent transversely to form two portions in angular relation 20 to each other, one of said portions having an inwardly bent end portion engageable under said shoulder, the other of said portions in the operative position of the clip extending above and substantially horizontally over the cover margin 25 and having a bent-under portion extending to a point adjacent said one of said portions with its free end engaged with the cover margin adjacent the edge of the latter, said bent-under portion being of a length to enable it to flex freely relative to the overlying portion when its free end is engaged with the cover margin, the cover having a top annular rib at its outer edge immediately inwardly of which the extremities of the bent-under portions of the clips lie when applied, said rib serving as a positive stop for said extremities to prevent their accidental dislodgement from the cover margin, the clips being entirely separable from the container and cover when moved to permit removal of the cover.

45 2. The combination with a container in the form of a jar, said container having an external downwardly faced shoulder, and a cover for the mouth of the container having a marginal portion overlying the container lip, of means for securing the cover on the container, said means comprising a plurality of clips each of which 50 comprises a strip of springy metal bent transversely to form two portions in angular relation to each other, one of said portions having an inwardly bent end portion engageable under said shoulder, the other of said portions in the operative position of the clip extending above and substantially horizontally over the cover margin and having a bent-under portion extending to a point adjacent 55 said one of said portions with its free end engaged with the cover margin adjacent the edge of the latter, said bent-under portion being of a length to enable it to flex freely relative to the overlying portion when its free end is engaged with the cover margin, the clips being entirely separable from the container and cover when moved to permit removal of the cover, and a wire received in the bends of the clips between their bent-under portions and the superjacent portions, the bends being so formed as to retain the wire, the 60 wire being offset so as to position the clips thereon and so as to lie closely adjacent the cover except where engaged in said bends.

tirely separable from the container and cover when moved to permit removal of the cover, and a wire received in the bends of the clips between their bent-under portions and the superjacent portions, the bends being formed so as to retain 5 the wire.

3. The combination with a container in the form of a jar, said container having an external downwardly faced shoulder, and a cover for the mouth of the container having a marginal portion overlying the container lip, of means for securing the cover on the container, said means comprising a plurality of clips each of which 10 comprises a strip of springy metal bent transversely to form two portions in angular relation 15 to each other, one of said portions having an inwardly bent end portion engageable under said shoulder, the other of said portions in the operative position of the clip extending above and substantially horizontally over the cover margin 20 and having a bent-under portion extending to a point adjacent said one of said portions with its free end engaged with the cover margin adjacent the edge of the latter, said bent-under portion being of a length to enable it to flex freely relative to the overlying portion when its free end is engaged with the cover margin, the clips being entirely separable from the container and cover when moved to permit removal of the cover, and a wire received in the bends of the clips between 25 their bent-under portions and the superjacent portions, the bends being so formed as to retain the wire and the wire being offset so as to position the clips on the wire.

4. The combination with a container in the 30 form of a jar, said container having an external downwardly faced shoulder, and a cover for the mouth of the container having a marginal portion overlying the container lip, of means for securing the cover on the container, said means 35 comprising a plurality of clips each of which comprises a strip of springy metal bent transversely to form two portions in angular relation to each other, one of said portions having an inwardly bent end portion engageable under said shoulder, 40 the other of said portions in the operative position of the clip extending above and substantially horizontally over the cover margin and having a bent-under portion extending to a point adjacent 45 said one of said portions with its free end engaged with the cover margin adjacent the edge of the latter, said bent-under portion being of a length to enable it to flex freely relative to the overlying portion when its free end is engaged with the cover margin, the clips being entirely separable 50 from the container and cover when moved to permit removal of the cover, and a wire received in the bends of the clips between their bent-under portions and the superjacent portions, the 55 bends being so formed as to retain the wire, the wire being offset so as to position the clips thereon and so as to lie closely adjacent the cover except where engaged in said bends.
